UNITED STATES PATENT OFFICE.

WILLIAM F. WAITE, OF PALMER, MASSACHUSETTS.

DESIGN FOR A TOOL-HANDLE WEDGE.

SPECIFICATION forming part of Design No. 33,919, dated January 15, 1901.

Application filed December 13, 1900. Serial No. 39,793. Term of patent 7 years.

To all whom it may concern:

Be it known that I, WILLIAM F. WAITE, a citizen of the United States of America, and a resident of Palmer, in the county of Hampden and State of Massachusetts, have invented and produced a new and useful Design for a Tool-Handle Wedge, of which the following is a full, clear, and exact description.

Reference is to be had to the accompanying drawings, in which the wedge of the new design is illustrated, and in which—

Figure 1 is a perspective view of the wedge in an upright position. Fig. 2 is a perspective view of the same in a horizontal position with its butt end forward, and Fig. 3 is a perspective view of the same in a horizontal position with its side forward. Fig. 4 is a front elevation of the wedge, and Fig. 5 is a sectional view taken on the plan indicated by the line 3 3, Fig. 4.

As shown in the drawings, the leading characteristic and essential feature of my design consists in the compound or multiple wedge, in which the two outer and substantially parallel wedges A A are united by the intermediate wedge B, the central plane of which is at right angles to the central planes of the wedges A A, and both said outer wedges hav-

ing in their two opposite edges the concavities *a a* near their tops, so that the faces of said edges have the superficial form shown by the boundary-lines of Fig. 5—that is, straight top *b*, straight lateral edge portions *d d*, each extending but a short distance below the said top and nearly perpendicular thereto, the opposite curved depressions, the lengths of which are considerably less than half the length of the wedge, and the straight lateral edge portions *d² d²*, which except for the interrupting concavities would be continuations of the edge-bounding lines *d* and which extend to and join the convex end *f*.

By imparting the concavities to the edges of the outer wedges, as shown, the upper portions of such wedges have imparted to them a distinctive aspect approximating that of a keystone.

Having now described my invention, what I claim, and desire to secure by Letters Patent, is—

The design for a tool-handle wedge as herein shown and described.

WM. F. WAITE.
